FASTENER APPLYING IMPLEMENT

Arthur H. Maynard, Warwick, R. I., assignor to
 Boston Wire Stitcher Company, Warwick, R. I.,
 a corporation of Maine

Application December 12, 1938, Serial No. 245,105

31 Claims. (Cl. 1-3)

This invention relates to improvements in fastener-applying implements for attaching papers and other sheets, securing tags and labels to articles of commerce and for use generally for fastening and stitching together various objects and articles.

One of the objects of the present invention is to provide an implement of the type indicated of light weight and compact construction to adapt it to be carried in the pocket or in a lady's purse or hand-bag for general use.

Another object of the present invention is to provide an implement of the type indicated having a coreless magazine with an open side through which fasteners are supplied and a fastener-applying lever constituting a closure for the open side of the magazine and movable relatively thereto for applying fasteners fed therefrom.

Another object of the invention is to provide an implement of the type indicated having means for latching or locking the parts in compact folded relationship, with the magazine and fastener-applying lever locked together to limit the relative movement therebetween, and with the lever releasable for movement away from the magazine to open the latter.

Another object of the present invention is to provide an implement of the type indicated so constructed and arranged that a single spring is operative to hold the magazine elevated with respect to the base and the fastener-applying arm raised with respect to the magazine.

Still another object of the present invention is to provide an implement of the type indicated having feeding means for the fasteners adapted to be automatically latched in retracted position and automatically released when the fastener-applying lever is moved to close the open side of the magazine.

Another object of the present invention is to provide an implement of the type indicated having a magazine of one-piece construction with a strut extending longitudinally thereof to brace the shear-plate at the rear of the throat or guideway for the fasteners and to provide a guide for the pusher and pusher-spring.

Still another object of the present invention is to provide an implement of the type indicated which is of extremely simple and compact construction and comprised of a minimum number of parts to adapt it for economical manufacture.

Further objects of the invention are set forth in the following specification, which describes a preferred form of construction of the invention,

by way of example only, as illustrated by the accompanying drawings. In the drawings:

Fig. 1 is a perspective view of a fastener-applying implement incorporating certain novel features of the present invention;

Fig. 2 is a perspective view of the implement illustrated with its base swung back through an arc of 180° with respect to the fastener-applying arm to adapt the implement to be used as a tacker;

Fig. 3 is a perspective view of the implement illustrated with the operating lever swung back through an arc of 180° with respect to the magazine to open the latter for the insertion of the fasteners;

Fig. 4 is a perspective view of the implement illustrated with its parts latched together in compact, folded relationship;

Fig. 5 is a longitudinal sectional view through the implement showing the spring for yieldingly holding the operating lever raised with respect to the magazine and the magazine raised with respect to the base and also illustrating the latching means on the lever and magazine for limiting the relative movement therebetween;

Fig. 6 is a part-sectional view of the implement showing the relationship of the parts at the completion of a fastener-applying operation;

Fig. 7 is a top plan view of the magazine showing the pusher mounted therein and the strut for guiding the pusher and bracing the shear-plate;

Fig. 8 is a part-sectional view of the magazine and base of the implement in side elevation showing the pusher latched in retracted position in the magazine and indicating the fastener-applying lever as being swung toward the magazine;

Fig. 9 is a part-sectional view of the implement showing the latch on the operating lever as being moved forwardly by its sliding engagement with the cam-face on the base;

Fig. 10 is a view similar to Fig. 9 showing the operating lever moved to closed position on the magazine and the latch moved forwardly and underlying the latching shoulder on the magazine;

Fig. 11 is a longitudinal sectional view through the implement showing the pusher as being rocked by the spring on the operating lever to release it from latched engagement with the magazine;

Fig. 12 is a part-sectional view similar to Fig. 9 showing the latch on the operating lever in engagement with a latching shoulder on the base

to hold the several parts in compact folded relationship;

Fig. 13 is a transverse sectional view taken on line 13-13 of Fig. 5 showing the relationship of the driver and staples and the hold-down lugs at the rear of the driver;

Fig. 14 is a transverse sectional view taken on line 14-14 of Fig. 10 showing the depending latching lug on the pusher engaged in the opening in the base to hold the pusher in retracted position; and

Fig. 15 is a transverse sectional view taken on line 15-15 of Fig. 6 showing the pusher in operative position in the magazine with its depending lug resting on the bottom wall thereof.

In the accompanying drawings the invention is illustrated as applied to a device for driving and clinching U-shaped staples, but it is to be understood that the implement may be used to apply other forms of fasteners. As herein illustrated the implement comprises a rectangular base 2 having a raised boss 3 at its forward end with clincher-grooves 4 formed therein and upwardly-projecting spaced stanchions 5 adjacent its rearward end having rearwardly-projecting ears 6. The forward edge of one of the stanchions 5 is provided with a rearwardly-inclined cam-face 7 and below the cam-face the stanchion is recessed to provide a latching shoulder 8. The base 2 projects rearwardly beyond the stanchions 5 to provide a stop 9 for a purpose as will appear later. Preferably, the base 2 is constructed in one piece blanked from sheet-metal stock with the boss 3 struck up therefrom and the clincher-grooves 4 stamped therein, while the stanchions 5 are folded upwardly at the sides of the base. The ears 6 projecting rearwardly from the stanchions 5 are drilled or otherwise pierced to provide aligned holes 10 for mounting a pivot-pin 11 having an annular recess 12 intermediate its ends.

The stapling arm 15 comprises a magazine 16 and an operating lever 17 constituted as a cover in which the magazine is adapted to be nested. The separable parts 16 and 17 of the arm 15 are both rockably mounted on the pivot-pin 11 for movement relatively to each other or together as a unit. The magazine 16 is of channel-shape in cross-section having a bottom wall 18 and upwardly-extending side walls 19 adapted to closely fit between the spaced stanchions 5 on the base 2. The side walls 19 of the magazine 16 are pierced adjacent their rearward ends with aligned holes adapted to receive the pivot-pin 11.

A shear-plate 20 projects upwardly from the bottom wall 18 of the magazine 16 at its forward end and flanges 21 project inwardly from the side walls 19 in spaced relation to the shear-plate to provide a throat or guideway 22 for the staples between the plate and the flanges. As herein illustrated the upper edge 23 of the shear-plate 20 is arched as shown in Fig. 13 of the drawings to accommodate arched crown staples 8 of the type illustrated and described in United States Letters Patent No. 2,052,553 to Cavanagh, dated September 1, 1936, the arch 23 being beveled rearwardly, see Fig. 5. Preferably, the bottom wall 18 of the magazine 16 is slotted rearwardly at its forward end adjacent the opposite side walls 19 and the portion between the slits is folded upwardly to form the shear-plate 20, while the projecting ends of the side walls are folded inwardly to form the flanges 21. As illustrated most clearly in Fig. 7, the slits extend rearwardly from the shear-plate 20 to provide clearance openings 24 at the rear of the throat 22. Hold-

down lugs 25 are provided at the rear of the throat 22, being in the form of tabs folded inwardly from the top of the opposite side walls 19 to overlie the staples at the forward end of the magazine. Intermediate the ends of the magazine 16 the side walls 19 are slotted and the slotted portions forced outwardly to provide guiding bosses 26 for the lever 17. Rearwardly of the bosses 26 a lug or projection is struck outwardly from one of the side walls 19 to provide a latching shoulder 27. Preferably, the upper edges of the side walls 19 of the magazine 16 adjacent the stanchions 5 are recessed or cut away on an arc as illustrated at 38, in Fig. 5, for a purpose that will appear later. The bottom wall 18 of the magazine 16 is provided with a latching shoulder 28 and, as illustrated in the present drawings, the shoulder 28 is formed by the front edge of an opening 29.

Extending longitudinally of the channel-shaped magazine 16 is a strut which may take the form of a rod 30 having a reduced end 31 adapted to engage in a hole in the shear-plate 20 with its annular shoulder 32 bearing against the rearward face of the plate. The opposite rearward end of the rod 30 projects through a hole 33 in the upright portion of a right-angular bracket 34 and seats in the annular recess 12 in the pivot-pin 11. The horizontal portion 35 of the bracket 34 underlies the pivot-pin 11 to hold the end of the rod 30 against upward displacement. Thus, the strut or rod 30 extends between the pivot-pin 11 and shear-plate 20 to brace the latter against displacement rearwardly and the rearward end of the rod seats in the annular recess 12 in the pivot-pin 11 to retain the latter in place. The rod 30 is assembled in the magazine by sliding the bracket 34 forwardly thereon, inserting the reduced forward end 31 of the rod into the hole in the shear-plate 20 and then seating its rearward end in the annular recess 12 in the pivot-pin 11. A coiled spring 36, to be described later, acting between a pusher 60 on the rod and the bracket 34 yieldingly holds the vertical and horizontal portions of the bracket in position against one side and the bottom of the pivot-pin 11.

The lever or cover 17 is of channel shape arranged in inverted relation to the magazine 16 and having a top wall 42 and depending side walls 43. The lever or cover 17 is slightly wider and longer than the magazine 16 so that the top wall 42 projects beyond the forward end of the magazine and its side walls 43 overlie the sides of the magazine and the sides of the stanchions 5 on the base 2. The side walls 43 of the lever 17 are pierced adjacent their rearward ends with aligned holes adapted to receive the laterally-projecting ends of the pivot-pin 11.

A staple-driver 44 is attached to the top wall 42 of the lever 17 to adapt it to reciprocate in the throat 22 of the magazine 16 as the lever is rocked toward and away from the latter. As herein illustrated, the driver 44 is formed by the forward narrower side of a sheet-metal angular plate 45, positioned on the bottom side of the top wall 42 of the lever 17 and fitting closely between the side walls 43 to hold it against twisting movement. The angular plate 45 may be attached to the top wall 42 of the lever 17 by a rivet 46 or any other suitable means such as welding.

A leaf-spring 47 has one end positioned between the angular plate 45 and the top wall 42 of the lever 17 and is connected to the latter

by the rivet 46 or other suitable means. The leaf-spring 47 is of a width substantially equal to the distance between the side walls 43 of the lever 17 and extends throughout a substantial portion of the length of the lever being generally curved in an arc from its point of attachment to its free end as illustrated in Fig. 3.

A latch 50 is mounted to slide on the side wall 43 of the lever 17 adjacent the side wall 19 of the magazine 16 having the latching shoulder 27. The latch 50, as illustrated in Figs. 12 and 14, is in the form of a sliding plate adapted to bear against the inside face of the side wall 43 and having ears 51 and 52 forming shoulders projecting from its opposite edges. The latch 50 is held in position on the lever 17 by means of a laterally-projecting shank 53 extending outwardly through an opening 54 in the side wall 43 with a finger-piece 55 at its outer end which overlies the outside face of the lever at the ends of the opening 54. The opening 54 in the side wall 43 of the lever 17 is of greater length than that of the shank 53 so that the latching plate 50 may be slid from the position shown in Fig. 9 to that shown in Fig. 10, or vice versa. Preferably a friction element 57 is provided between the latch 50 and the side wall 43 of the lever 17 to yieldingly hold the latch in one or the other of its two positions on the lever. As illustrated in Figs. 6 and 14 the friction element 57 comprises an arched leaf-spring of rectangular form mounted on the shank 53 of the latch 50 with its central portion bearing against the latch and its ends bearing against the inside face of the side wall 43 of the lever. As illustrated in Fig. 9, the rearward edge 56 of the latch 50 adjacent the ear 52 is inclined upwardly for cooperation with the cam-face 7 on the stanchion 5 of the base 2 to automatically slide the latch forwardly during the movement of the lever 17 to close the open side of the magazine 16. The ear 51 at the forward edge of the latch 50 normally underlies the latching shoulder 27 on the side wall 19 of the magazine 16 as illustrated in Figs. 5 and 6, but the latch may be slid rearwardly to release it from the shoulder 27 as illustrated in Fig. 9, or to engage the rearward ear 52 with the latching shoulder 8 on the stanchion 5 of the base as illustrated in Fig. 12.

In accordance with the present invention a supply of the arched crown staples s may be inserted into the channel-shaped magazine 16 through its open top to be wholly supported therein by the ends of their legs resting upon the bottom wall 18. The crowns of the staples s extend laterally across the interior of the magazine 16 which is so constructed that the opposite legs of the staples lie closely adjacent the inner faces of its spaced walls 19. Thus, the magazine has no core as a support for the staples which simplifies its construction and reduces the number of parts.

The staples s are advanced in the magazine by a pusher 60 slidably mounted therein at the rear of the staples s. The pusher 60 has a top wall 61 with depending front and rear walls 62 and 63 and opposite side walls 64 which project beyond the front and rear walls to provide forward and rearward rails or flanges 65 and 66. The front wall 62 of the pusher 60 is provided with a slotted opening 67, see Fig. 14, and the back wall 63 is provided with a hole 68 through which the rod 30 extends. The opposite side walls 64 and forwardly- and rearwardly-projecting side flanges or rails 65 and 66 of the pusher 60 fit 75 47 is tensioned and the latch 50 is moved for-

closely against the inside faces of the side walls 19 of the magazine 16 which, together with the rod 30, guide the pusher in its sliding movement. As illustrated in Figs. 6 and 7, the ends of the 5 forwardly-projecting rails 65 are adapted to engage the opposite legs of the rearmost staple in the magazine, the forward upper edges of the rails being beveled as indicated by the reference character 69 in Fig. 11 to adapt the pusher to 10 be cammed rearwardly by the driver 44. Forwardly of the rear wall 63 the side walls 64 of the pusher 60 are cut away at the bottom as 15 illustrated in Fig. 11 to adapt the pusher to rock about the bottom edge of its rear wall as a pivot from the position illustrated in Fig. 6 to that 20 illustrated in Fig. 8. The lower edge of the front wall 62 which depends below the side walls 64 and the bottom edges of the forwardly-projecting rails 65 constitutes a lug or latch 70 25 adapted to enter the opening 29 in the bottom wall 18 of the magazine 16 and engage the latching shoulder 28 when the pusher is retracted, as shown in Fig. 8. As illustrated in Fig. 14 the depending lug 70 is of reduced width to facilitate 30 its entrance into the opening 29. When the pusher is rocked to engage its depending lug 70 with the latching shoulder 28 in the bottom wall 18 of the magazine 16 the rearwardly-extending rails 66 project upwardly above the arcuately-recessed portions 38 of the side walls 19 as 35 illustrated in Fig. 8. The pusher 60 is advanced in the magazine by means of a compression spring 71 coiled about the rod 30 and acting between the angular bracket 34 and the rearward wall 63 of the pusher. One preferred form of construction of the invention having been described in detail its mode of operation is explained as follows.

To open the magazine 16 to adapt it to receive 40 a supply of staples s the latch 50 is manually operated to slide it rearwardly to the position illustrated in Fig. 9 whereby to release its ear 51 from the shoulder 27. The lever 17 is then swung on the pivot-pin 11 outwardly away from the magazine 16 to the position illustrated in Figs. 45 3 and 7. The pusher 60 is next retracted by 50 manual pressure applied to slide it rearwardly and rock its front wall 62 downwardly when the depending lug 70 overlies the opening 29 in the bottom wall 18 of the magazine 16. The pusher 60 will thus rock about the bottom edge of its rear wall 63 to cause the lug 70 to enter the opening 29 and engage the shoulder 28 to hold the pusher retracted against the action of the spring 71. A supply of U-shaped staples s having arched 55 crowns as illustrated in Figs. 3 and 13, and preferably in the form of a self-contained stick, is inserted in the magazine 16 between its spaced side walls 19 with the ends of their legs resting against the bottom wall 18. The staples s are 60 thus wholly supported on the bottom wall 18 of the magazine 16.

After the magazine 16 has been loaded with a supply of staples s the lever 17 is swung back toward the magazine 16 in the manner indicated by dash lines in Fig. 8. During this movement of the lever 17 the free end of the spring 47 engages with and slides along the upper edges of the spaced stanchions 5 as shown in Fig. 9 and 70 the inclined edge 56 of the latch 50 engages the inclined cam-face 7 on the forward end of one of the stanchions. Upon further continued movement of the lever 17 from the position shown in Fig. 9 to that shown in Fig. 10 the spring 47 is tensioned and the latch 50 is moved for-

wardly by the cam-face 7 until its forwardly-projecting ear 51 underlies the latching shoulder 27 on the side 19 of the magazine 16. During this swinging movement of the lever 17 with respect to the magazine 16 the driver 44 enters the throat 22. When manual pressure on the lever 17 is released the tensioned spring 47 acting against the stanchions 5 causes the lever to move upwardly away from the magazine 16 and base 2 until the forwardly-projecting ear 51 on the latch 50 engages the latching shoulder 27 on the side of the magazine. Thereafter the magazine 16 moves upwardly with the lever 17 until the end of the spring 47 engages the top edges of the side walls 19 of the magazine 16 as shown in Fig. 11. The stapling arm 15 comprising both the lever 17 and magazine 16 are then yieldingly held in raised position above the base 2 by the engagement of the end of the spring 47 with the top edges of the stanchions 5 on the base, see Fig. 5. During this movement of the magazine 16 away from the base 2 the rearwardly-extending rails 66 on the pusher 60 are engaged by the end of the spring 47 to thereby rock the pusher about the bottom edge of its rear wall 63 in a clockwise direction as illustrated in Fig. 11, the arcuate recesses 38 in the side walls 19 of the magazine providing for this action. The rocking movement of the pusher 60 automatically releases its depending lug 70 from its engagement with the shoulder 28 at the forward end of the opening 29 in the magazine 16 and the spring 71 then acts to advance the pusher 60 in the magazine 16 to feed the staples *s* toward the throat 22. The implement is then ready for a staple-driving operation.

When the implement is to be used to apply clinched fasteners it may be supported on a desk or the like or held in the hand. The work *w* to be stapled is placed on the boss 3 at the forward end of the base 2 and the lever 17 is depressed against the action of the spring 47, thereby causing the lever and magazine 16 to rock as a unit about the pivot-pin 11 until the forward end of the magazine engages with and clamps the work *w* against the boss 3. Continued pressure on the lever 17 causes it to move relatively to the magazine 16 to the position illustrated in Fig. 6 and the driver 44 to descend through the throat 22 in the magazine. Thus, the foremost staple *s* is sheared from the remainder of the stick and driven through the throat 22 to cause its legs to penetrate the work and to be clinched by the grooves 4 in the boss 3 on the base 2. During the driving of the foremost staple *s* the next adjacent staple straddles the shear-plate 20 and is supported thereon to provide a reaction to the shearing force of the driver 44 in severing the foremost staple, the rearwardly-inclined edge 23 on the shear-plate serving to guide the staples thereover as they are advanced by the pusher 60. Upon release of the lever 17 the spring 47, acting against the top edges of the stanchions 5, rocks the lever upwardly away from the base 2 until the forwardly-projecting ear 51 on the latch 50 engages the shoulder 27 on the magazine 16, after which the spring acts to raise the magazine 16 away from the base 2. The single spring 47 thus serves a dual purpose to normally hold the lever 17 raised with respect to the magazine 16 and the magazine raised with respect to the base 2. It will be noted that several of the staples *s* of the stick at the rear of the driver 44 underlie the hold-down lugs 25 at the forward end of the magazine 16 to prevent

the end of the stick from rising with the driver. As the driver 44 is withdrawn from the throat 22 the whole supply of staples *s* is advanced by the pusher 60 to position the next foremost staple in the throat. The device may be operated continuously by depressing the lever 17 until the supply of staples *s* is exhausted.

When the implement is to be used as a tacker the base 2 is swung back through an arc of 180° with respect to the arm 15 to the position shown in Fig. 2. During this movement the rearward edge of the top wall 42 of the lever 17 enters between the rearwardly-extending ears 6 beneath the rearwardly-extending stop 9 on the base 2, the movement of the lever thus being limited by the engagement of the rearward end of the top wall 42 with the stop 9. The lever 17 may then be depressed with respect to the magazine 16, as explained above, to drive the staples *s* into the work to tack one article to another.

The implement may be folded into small compass with its parts latched together to adapt it to be carried in the pocket as a portable device, the parts being pressed together to the position illustrated in Figs. 4 and 10 and the latch 50 then slid rearwardly to engage its ear 52 with the latching shoulder 8 on the stanchion 5 of the base 2, see Fig. 12. When it is desired to use the implement again the latch 50 is slid forwardly and the parts are moved automatically by the spring 47 to return them to operative position as illustrated in Fig. 5.

It will be observed from the foregoing that the present invention provides an extremely simple and compact fastener-applying device adapted for use as an ordinary desk stapler or to be carried in the pocket, purse or hand-bag as a portable implement. It will be observed further that the implement has a minimum number of parts so constructed and arranged as to adapt it for economical manufacture and assembly. It will also be observed that the implement is of rugged construction to adapt it for continuous use over long periods of time without requiring replacement or repair of its parts.

While there is herein illustrated and described a preferred embodiment of the invention, it is to be understood that various modifications may be made in the structure and arrangement of the parts of the device without departing from the spirit or scope of the invention. Therefore, without limiting myself in this respect, I claim:

1. In a device of the type indicated, a base carrying clinching means, latching means on the base, a magazine mounted for movement toward and away from said base, said magazine being adapted to hold a supply of fasteners, fastener-applying means movable relatively of said magazine to apply fasteners fed therefrom, and means on the fastener-applying means engageable with the latching means on the base for latching the magazine and fastener-applying means in position closely adjacent said base.

2. In a device of the type indicated, a magazine having an open side extending longitudinally thereof, a lever movable relatively of the magazine for closing the open side thereof, a driver operative by the lever, said lever being movable toward the magazine to drive fasteners fed therefrom and away from the magazine to open the latter to receive a supply of fasteners through its open side, and means for retaining the lever in closed position on the magazine

while permitting relative movement therebetween to apply the fasteners to the work.

3. In a device of the type indicated, a magazine having an open side extending longitudinally thereof, a lever for closing the open side of the magazine, a driver carried by the lever, said lever being movable toward the magazine to drive fasteners fed therefrom and away from the magazine to open the latter to receive a supply of fasteners through its open side, cooperating latching means on the magazine and lever to retain the latter closed with respect to the magazine while permitting relative movement therebetween to apply the fasteners to the work, and means for operating the cooperating latching means during the closing movement of the lever to latch the magazine and lever together.

4. In a device of the type indicated, a base having clinching means thereon, a magazine pivotally mounted on the base for movement toward and away from the latter, said magazine having an open side through which the fasteners are supplied thereto, latching means on the magazine, a lever for closing the open side of the magazine, a slidably latch on the lever, and means on the base for moving the latch into engagement with the latching means on the magazine when the lever is swung to closed position thereon.

5. In a device of the type indicated, a base having clinching means thereon, a magazine for fasteners mounted for movement toward and away from the base, fastener-applying means movable relatively of the magazine for driving fasteners fed therefrom, and a single means for releasably latching the fastener-applying means to the magazine and the fastener-applying means and magazine to the base.

6. In a device of the type indicated, a base having clinching means thereon, a latching shoulder on the base, a magazine mounted on the base for movement toward and away from the latter and having a latching shoulder, fastener-applying means movable relatively of the magazine for driving fasteners fed therefrom, and a latch on the fastener-applying means movable into engagement with the latching shoulder on the magazine or the latching shoulder on the base.

7. In a device of the type indicated, a base having clinching means thereon, latching means on the base, a magazine mounted on the base for movement toward and away from the latter and having a throat through which the fasteners are driven, said magazine having an open side through which the fasteners are supplied and latching means, a lever adapted to close the open side of the magazine, a driver carried by the lever for reciprocation in the throat in the magazine, resilient means for holding the magazine raised with respect to the base and the lever raised with respect to the magazine, and a means on the lever engageable with the latching means on the magazine or the latching means on the base.

8. In a device of the type indicated, a base having clinching means thereon, stanchions on said base projecting upwardly from the sides thereof, a magazine pivoted on the stanchions for movement toward and away from the base, a lever movable relatively of the magazine and having a driver for driving fasteners fed therefrom, and a single leaf-spring having one end attached to the lever and its opposite end engageable with the magazine and the stanchions

on the base to hold the lever raised with respect to the magazine and the magazine raised with respect to the base.

9. In a device of the type indicated, a base having clinching means thereon, a magazine mounted for movement toward and away from the base, fastener-applying means movable relatively of the magazine for driving fasteners fed therefrom, and a spring carried by the fastener-applying means and directly engageable with both the magazine and the base to hold the fastener-applying means raised with respect to the magazine and the magazine raised with respect to the base.

10. In a device of the type indicated, a channel-shaped magazine having a bottom wall, side walls projecting upwardly from the bottom wall and an open top, said bottom wall of the magazine forming a rest for directly supporting a supply of fasteners and having latching means intermediate its ends, a pusher in the magazine having latching means for cooperation with the latching means on the bottom wall of the magazine, a spring for advancing the pusher in the magazine, said latching means on the pusher being engageable with the latching means on the bottom wall of the magazine when the pusher is manually retracted to hold the latter against the action of the spring, and fastener-applying means movable relatively of the magazine for driving fasteners therefrom.

11. In a device of the type indicated, a magazine having an opening therein through which fasteners are supplied, a closure for closing the opening in the magazine, a pusher in the magazine, means for advancing the pusher in the magazine, and means adjacent the rearward end of the magazine for holding the pusher retracted therein, said closure being so constructed and arranged as to actuate the holding means to release the pusher.

12. In a device of the type indicated, a magazine having an open side and latching means intermediate its ends, a lever for closing the open side of the magazine, said lever being movable with respect to the magazine to open the latter to receive a supply of fasteners, a pusher in the magazine, and resilient means for advancing the pusher, said pusher being manually rockable to engage it with the latching means on the magazine to hold it retracted against the action of the resilient means and adapted to be automatically rocked by the lever to release it from engagement with the latching means on the magazine.

13. In a device of the type indicated, a base, a magazine mounted for movement toward and away from the base, said magazine having an open side and latching means intermediate its ends, a lever for closing the open side of the magazine, said lever being movable with respect to the magazine to open the latter to receive a supply of fasteners, a pusher in the magazine for advancing the fasteners and rockable into engagement with the latching means on the magazine, means on the lever engageable with the pusher to rock the latter to release it from engagement with the latching means on the magazine, and a driver operative by the lever for driving fasteners from the magazine.

14. In a device of the type indicated, a magazine having an open side through which fasteners are supplied, a lever for closing the open side of the magazine, a driver operative by the lever, resilient means carried by the lever and

engageable with the magazine to yieldingly hold the lever raised with respect to the magazine, a pusher in the magazine, means for advancing the pusher, and interlocking means on the magazine and pusher for holding the latter retracted, said pusher being manually rocked to engage the interlocking means and automatically rocked by the resilient means on the lever to release the interlocking means.

15. In a device of the type indicated, a channel-shaped magazine having a throat at one end through which the fasteners are driven and a bottom wall adapted to directly support a supply of fasteners thereon, a shear-plate at the rear of the throat having its upper edge inclined rearwardly, and fastener-applying means movable relatively of the magazine for driving fasteners therefrom.

16. In a device of the type indicated, a channel-shaped magazine having a throat through which the fasteners are driven and a bottom wall adapted to directly support a supply of fasteners having arched crowns, a shear-plate at the rear of the throat having its upper edge arched to correspond to the arched crowns of the fasteners, and fastener-applying means movable relatively of the magazine for driving fasteners therefrom.

17. In a device of the type indicated, a magazine having a throat through which the fasteners are driven, said magazine being channel-shaped and having side walls and a bottom wall adapted to directly support a supply of fasteners mounted therein between the side walls with the ends of the legs directly engaging the bottom wall, a shear-plate at the rear of the throat, hold-down lugs projecting inwardly from the side walls of the magazine at the opposite sides of the shear-plate, and fastener-applying means movable relatively of the magazine for driving fasteners therefrom.

18. In a device of the type indicated, a hollow channel-shaped magazine having a throat through which the fasteners are driven and a bottom wall adapted to directly support a supply of fasteners, a shear-plate at the rear of the throat and spaced from the sides of the magazine to adapt the legs of the fasteners to pass therebetween, means for bracing the shear-plate against displacement rearwardly, and fastener-applying means movable relatively of the magazine for driving fasteners therefrom.

19. In a device of the type indicated, a channel-shaped magazine having a throat at one end through which the fasteners are driven and a bottom wall adapted to directly support a supply of fasteners, a shear-plate at the rear of the throat, a strut extending longitudinally of the magazine with one end rigidly connected thereto and its opposite end engaging the shear-plate to brace the latter against displacement rearwardly, and fastener-applying means movable relatively of the magazine for driving fasteners therefrom.

20. In a device of the type indicated, a magazine having a bottom wall with one end folded upwardly and side walls with their ends folded inwardly in spaced relation to the folded end of the bottom wall to form a throat therebetween, said magazine being adapted to hold a supply of fasteners extending thereacross and supported therein by the engagement of the ends of their legs with the bottom wall of the magazine, an abutment at the end of the magazine opposite the throat, a strut extending between the abutment and the upwardly-folded end of the bot-

tom wall to brace the latter against displacement rearwardly, and fastener-applying means movable relatively of the magazine for driving fasteners therefrom.

5 21. In a device of the type indicated, a hollow magazine having a throat through which the fasteners are driven and a bottom wall adapted to directly support a supply of fasteners, a shear-plate at the rear of the throat, an abutment at the end of the magazine opposite the throat, a strut extending between the abutment and the shear-plate, a pusher in the magazine having depending flanges embracing the strut, a spring acting between the abutment and pusher for advancing the latter in the magazine, and fastener-applying means movable relatively of the magazine for driving fasteners therefrom, said strut acting to brace the shear-plate against displacement rearwardly and providing a guide for the pusher.

22. In a device of the type indicated, a magazine having a throat through which the fasteners are driven and a bottom wall adapted to directly support a supply of fasteners and spaced side walls, a shear-plate in the magazine at the rear of the throat, an abutment adjacent the end of the magazine opposite the shear-plate, a pusher in the magazine having depending end flanges with openings therein and rails at its sides projecting forwardly and rearwardly therefrom, a strut extending between the abutment and shear-plate and through the openings in the depending flanges of the pusher, a coil-spring surrounding the strut and acting between the abutment and pusher for advancing the latter, and fastener-applying means movable relatively of the magazine for driving fasteners therefrom, said shear-plate being supported by the strut against displacement rearwardly and said pusher being guided by the strut and the rails at its sides.

23. In a device of the type indicated, a base having clinching means thereon, stanchions on said base projecting upwardly from the sides thereof, a magazine pivotally mounted on the stanchions for movement toward and away from the base and having an open side through which the fasteners are supplied, a lever pivotally mounted for movement relatively of the magazine to open or close the open side of the latter, a driver carried by the lever for driving fasteners from the magazine, and a single resilient element engageable with the lever, magazine and base to hold the lever raised with respect to the magazine and the magazine raised with respect to the base.

24. In a device of the type indicated, a channel-shaped magazine having a bottom wall for directly supporting fasteners and an open top through which the fasteners are supplied, the bottom wall of said magazine having a transverse latching shoulder, a pivoted lever for closing the open side of the magazine and carrying a driver for driving the fasteners from the magazine, a pusher in the magazine, and resilient means for advancing the pusher, said pusher having a depending lug engageable with the transverse shoulder on the bottom wall of the magazine to hold the pusher retracted against the action of the resilient means to adapt fasteners to be supplied to the magazine through its open top.

25. In a device of the type indicated, a base, a magazine mounted for movement toward and away from the base, fastener-applying means mounted for movement relative to the magazine,

the device being operated to drive a fastener by moving the magazine toward the base to a position closely adjacent thereto and moving the fastener-applying means relative to the magazine to a position closely adjacent the latter, and cooperating means on the fastener-applying means and base comprising a manually-operable member for releasably latching the parts in their closely compacted inoperative relationship.

26. In a device of the type indicated, a base, a magazine for fasteners, a manually-operable lever overlying the magazine, a driver carried by the lever, said base, magazine and lever being so constructed and arranged as to adapt the lever to be moved to a position closely adjacent the magazine and the latter be moved closely adjacent the base to drive a fastener, and cooperating means on the lever and base comprising a manually-operable member for releasably latching the parts in their closely compacted relationship.

27. In a device of the type indicated, a base, a magazine for fasteners, a manually-operable lever overlying the magazine, fastener-applying means operable from the lever, resilient means for holding the magazine raised from the base and the lever raised from the magazine, said magazine, lever and base being so constructed and arranged as to adapt the lever to be moved to a position closely adjacent the magazine and the latter to be moved to a position closely adjacent the base against the action of the resilient means to drive a fastener, and cooperating means on the lever and base comprising a manually-operable member for releasably latching the parts in their closely compacted inoperative relationship.

28. In a device of the type indicated, a base, a channel-shaped magazine for fasteners, an inverted channel-shaped lever adapted to telescope over the magazine, a driver mounted on said lever, means for pivotally connecting the base, magazine and lever, resilient means for holding the magazine raised from the base and the lever raised from the magazine, said device being operated to drive a fastener by moving the lever to cause it to telescope over the magazine and to move the latter toward the base, and manually-operable means for releasably latching the parts in their closely compacted relationship to prevent operation of the device to apply the fasteners.

- 5 29. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and its opposite end seated in the recess in the pivot-pin to brace the shear-plate and hold the pivot-pin against movement laterally of the magazine, and means for holding the end of the strut seated in the recess in the pivot-pin.
- 10 30. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, and a right-angular bracket having an upright portion through which the strut extends and a base-portion positioned between the pivot-pin and the bottom of the magazine to hold the end of the strut seated in the recess in the pivot-pin.
- 15 31. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, a right-angular bracket having an upright portion through which the strut extends and a base-portion positioned between the pivot-pin and the bottom of the magazine, a pusher slidable on the strut, and a coil spring on the strut between the pusher and upright portion of the bracket whereby the spring yieldingly retains the bracket against the pivot-pin, the pivot-pin retains the bracket against vertical displacement and the bracket retains the end of the strut seated in the recess in the pivot-pin.
- 20 32. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, and a right-angular bracket having an upright portion through which the strut extends and a base-portion positioned between the pivot-pin and the bottom of the magazine to hold the end of the strut seated in the recess in the pivot-pin.
- 25 33. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, a right-angular bracket having an upright portion through which the strut extends and a base-portion positioned between the pivot-pin and the bottom of the magazine, a pusher slidable on the strut, and a coil spring on the strut between the pusher and upright portion of the bracket whereby the spring yieldingly retains the bracket against the pivot-pin, the pivot-pin retains the bracket against vertical displacement and the bracket retains the end of the strut seated in the recess in the pivot-pin.
- 30 34. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, and a right-angular bracket having an upright portion through which the strut extends and a base-portion positioned between the pivot-pin and the bottom of the magazine to hold the end of the strut seated in the recess in the pivot-pin.
- 35 35. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, a right-angular bracket having an upright portion through which the strut extends and a base-portion positioned between the pivot-pin and the bottom of the magazine, a pusher slidable on the strut, and a coil spring on the strut between the pusher and upright portion of the bracket whereby the spring yieldingly retains the bracket against the pivot-pin, the pivot-pin retains the bracket against vertical displacement and the bracket retains the end of the strut seated in the recess in the pivot-pin.
- 40 36. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, and a right-angular bracket having an upright portion through which the strut extends and a base-portion positioned between the pivot-pin and the bottom of the magazine to hold the end of the strut seated in the recess in the pivot-pin.
- 45 37. In a device of the type indicated, a magazine having a throat at one end through which the fasteners are driven and a shear-plate at the rear of the throat, a pivot-pin extending through the magazine at the end opposite the throat and having a recess intermediate its ends, a strut extending longitudinally of the magazine with one end bearing against the shear-plate and the opposite end seated in the recess in the pivot-pin, and a right-angular bracket having an upright portion through which the strut extends and a base-portion positioned between the pivot-pin and the bottom of the magazine to hold the end of the strut seated in the recess in the pivot-pin.

ARTHUR H. MAYNARD.
